US00D947601S

(12) **United States Design Patent** (10) Patent No.: **US D947,601 S**
(45) Date of Patent: ** Apr. 5, 2022

(54) **CARBONATION MECHANISM**

(71) Applicant: **SODASTREAM INDUSTRIES LTD.**,
Kfar Saba (IL)

(72) Inventors: **Guy Danieli**, Jerusalem (IL); **Amit Avigdor**, Kibutz Bahan (IL); **Doron Krom**, Zichron Yaakov (IL); **Oren Shalev**, Ashdod (IL); **Allan Ring**, Mercaz Shapira (IL); **Avi Cohen**, Jerusalem (IL); **Dvir Brand**, Hod Hasharon (IL); **Amnon Shkedi**, Karkur (IL)

(73) Assignee: **SODASTREAM INDUSTRIES LTD.**,
Kfar Saba (IL)

(**) Term: **15 Years**

(21) Appl. No.: **29/721,594**

(22) Filed: **Jan. 22, 2020**

(30) **Foreign Application Priority Data**

(57) **CLAIM**

The ornamental design for a carbonation mechanism, as shown and described.

DESCRIPTION

FIG. 1 is a front, left side, top perspective view of a carbonation mechanism showing our new design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan thereof.

The broken lines shown portions of the carbonation mechanism that form no part of the claimed design.

1 Claim, 5 Drawing Sheets
